[57] CLAIM

The ornamental design for the vegetation barrier, as shown
and described.

DESCRIPTION

FIG. 1 is a top view of a vegetation barrier;
FIG. 2 is a front edge view with the opposite view being
identical in appearance, with the exception of the pair of
slots provided along the front edge view;
FIG. 3 is a bottom view of the vegetation barrier shown in
FIG. 1;
FIG. 4 is a left side view thereof;
FIG. 5 is a right side view thereof; and,
FIG. 6 is a top view of the vegetation barrier as shown in
FIG. 1, shown in a curved position.
